UNITED STATES PATENT OFFICE.

LINDSAY C. PRITNER, OF JOHNSTOWN, PENNSYLVANIA.

TRUCK FRAME.

Application filed November 6, 1922. Serial No. 599,219.

To all whom it may concern:

Be it known that I, LINDSAY C. PRITNER, a citizen of the United States, and a resident of Johnstown, in the county of Cambria and State of Pennsylvania, have invented certain new and useful Improvements in Truck Frames; and I do hereby declare the following to be a full, clear, and exact description of my invention, such as will enable others skilled in the art to which it appertains to make and use the same.

My invention relates to a truck frame adapted for use in trucks of railway cars, and the principal parts of this frame are composed of one integral sheet of metal, which is cut or punched in its various portions to the shapes and sizes desired and flanged and then bent around its intermediate portion so as to produce a hollow structure of great strength and rigidity, comprising the various members of what is known as an integral arch bar type of truck side frame.

The plate forming the principal members of my truck frame has flanges formed on various of the edges thereof, and in accordance with my invention some of these flanges are wider than others and adapted to be overlapped, and in certain locations are secured together by electric or blow-pipe welding. This welding is preferably accomplished by providing circular or other shaped holes in the outer or in the more accessible one of the overlapping flanges and then filling these holes with fused metal, which is fused to both plates in such a way as to firmly secure them together.

The overlapping portions of the flanges are preferably arranged only on certain of the members and in some cases on certain portions of the said members in such a way as to provide the strength desired in each part with a minimum amount of work and material in accomplishing this. Other members have inturned flanges which are substantially opposite or in line with each other, but with their edges close together or spaced apart as desired.

I prefer to form the pedestal tie bars integral with the rest of the structure, thus forming a continuation of the bottom arch bar.

Having thus given a general description of my invention, I will now, in order to make the matter more clear, refer to the annexed sheet of drawings, which form part

of this specification, and in which like characters refer to like parts:—

Figure 1 is a side elevation of my improved truck frame; Figure 2 is a top plan view thereof; Figure 3 is an end elevation; Figure 4 is a cross sectional elevation taken on the line IV—IV of Figure 2; Figure 5 is a central cross section of the bottom arch bar taken on the line V—V of Figure 1; Figure 6 is a cross section of the bottom arch bar member taken on the line VI—VI of Figure 1; Figure 7 is a cross section of one of the end members of the frame which rests on the tops of the journal boxes taken on the line VII—VII of Figure 1; Figure 8 is a cross section of the inclined tension member taken on the line VIII—VIII of Figure 1; Figure 9 is a partial cross sectional plan through the lower portions of the truck columns taken on the line IX—IX of Figure 1; looking downwardly; Figure 10 is a cross section of a part of the pedestal tie bar taken on the line X—X of Figure 1, and Figure 11 is a horizontal cross section through the upper portion of one of the truck columns showing it and the attached column guide plate secured thereto taken on the line XI—XI of Figure 1.

Referring now to the characters of reference on the drawings:—1 is the upper portion of the plate which forms the top arch bar member, 2 are the integral side portions thereof, 3 are the triangular openings with rounded corners, 4 is the inwardly projecting flanged portion of the metal forming the boundaries of the triangular openings 3, 5 are the inturned flanges at the upper portion of the bolster opening, 6 indicates the bolster opening in general, 7 are the inturned flanges forming the boundaries of the upper side portions of the bolster openings, these flanges overlapping at this place; 8 are the column guide plates or pads which are secured to the flanges 7, 9 is the inturned flange portion at the lower side of the bolster opening which forms the upper portion of the central part of the bottom arch bar member, 10 are the inturned flanges on the ends of the frame which rest on the journal boxes and are continued on the inclined tension members as illustrated, 11 are the bottom inturned overlapping flanges of the bottom arch bar and part of the pedestal tie bar; 12 indicates the welded or fused material which holds the portions together and which is preferably fused into holes in one portion and to and against

the adjacent portion; and 13 are the ends of the inturned flanges of the diagonal tension member on the right hand side, which flanges are shorter than those on the left hand side, although both of them may be of the same length if desired. Those on the right hand side are shorter than those on the other side to obviate the difficulty of continuing the flange around the curve between the diagonal tension member and the inner portion of the pedestal tie bar member, although my frame may be constructed in either manner. 14 are the extension portions of the pedestal tie bar to assist in forming and bending the same in the dies; 15 are the end portions of the pedestal tie bars, which overlap as shown; 16 are the journal box bolt holes in the pedestal tie bars; 18 are corresponding holes in the lower flanges of the upper end portions of the frame; 17 are reinforcing plates inserted within the upper end portions to reinforce them and form nut locks for the heads of the journal box bolts; 19 is the spring plank, which may be secured to and within the bottom portion of the bolster opening in any manner, and 20 are the springs, these portions being indicated in dotted lines.

My frame has its principal members formed of one plate, preferably of rolled steel, which is cut or sheared to its shape when the plate is cold, and it may then be heated if desired and placed in a flanging press and the various flanges formed thereon, then it is placed in other apparatus and its intermediate portion is bent, and then the two halves are pressed together so that a hollow structure is formed having its members of approximately rectangular cross section with rounded corners, some of these having overlapping flanges and others having opposite flanges, either abutting or spaced apart. The various portions are then secured together by welding as indicated at 12 in the manner previously described.

The column guide plates 8 may also be secured to the frame by means of welding, or if desired I may omit these plates and use the bodies of the columns as the column guides, as this part of the construction is quite strong and stiff owing to its double thickness of plate due to overlapping the flanges thereof. After this is done reinforcing plates 17, having their ends turned up, are inserted in the ends and the truck frame may then be assembled in a truck and secured to the journal boxes, the spring plank, etc., mounted, the springs inserted, and the bolster placed therein in the usual manner.

When the frame is pressed together certain of the flanges are overlapping each other with their sides contiguous and in close contact, and when these are welded together they add strength and stiffness to the structure as compared with a single flange.

By reason of my construction the amount of welding is very much reduced and simplified as compared with other methods of connecting the parts.

Although I have shown and described my invention in considerable detail, I do not wish to be limited to the exact and specific details thereof as shown and described, but may use such modifications in, substitutions for, or equivalents thereof as are embraced within the scope of my invention or as pointed out in the claims.

Having thus described my invention, what I claim and desire to secure by Letters Patent is:

1. A truck frame composed of one metal plate provided with inwardly extending overlapping integral flanges secured together.
2. A truck frame composed of one metal plate, portions of which on each side of the median line are bent toward each other, spaced apart, and provided with inwardly projecting flanges, some of which are overlapping and secured together.
3. A truck frame composed of one metal plate, portions of which on each side of the median line are bent toward each other, spaced apart, and provided with inwardly projecting flanges, some of which are overlapping and secured together, and others are opposite and spaced apart.
4. An integral truck frame, composed of a single plate, forming various members, provided with integral flanges projecting inwardly and forming parts of the said members, some of the flanges overlapping and secured together and others opposite and with their edges spaced apart.
5. A truck frame composed of a single plate bent with its two portions opposite and apart and provided with integral flanges projecting inwardly and forming parts of the various members, some of the flanges being overlapped and secured together, other flanges being opposite and spaced apart, and a reinforcing member with upturned ends mounted within the upper end portions adapted to strengthen the same.
6. A truck frame comprising a single plate bent around its intermediate portion with its two parts spaced opposite each other, openings formed therein, and integral in-turned flanges around said openings, some of which are overlapping and secured together.
7. A truck frame comprising a single plate bent around its intermediate portion with its two parts spaced opposite each other, openings formed therein, integral in-turned flanges around said openings, some of which are overlapping and secured together, and other flanges are opposite and spaced apart.
8. A truck frame comprising a single plate

cut into the shape desired to form the various members, including a top arch bar member, a bottom arch bar member, inclined tension members, and column guide members, the side portions of which are opposite, spaced apart, and provided with inturned flanges, some of which are overlapping and secured together.

9. A truck frame comprising a single plate cut into the shape desired to form the various members, including a top arch bar member a bottom arch bar member, inclined tension members, and column guides, the side portions of which are opposite and spaced apart and provided with inturned flanges, some of which are overlapping and secured together, and other flanges opposite and spaced apart.

10. A truck frame comprising a single plate composing the various members, bent around its intermediate portion with its two opposite faces spaced apart, integral flanges extending inwardly from the various members thereof, some of which flanges are overlapping and secured together, and other members having shorter flanges, which are opposite, with their adjacent edges spaced apart.

11. A truck frame comprising a single plate, the two approximate halves of which are cut to form the various members, and bent about its intermediate portion, inwardly projecting integral flanges on certain of the members, the members of one-half being narrower than those of the other half by an amount substantially equal to the thickness of the plate, whereby certain of the flanges are overlapping, said flanges being welded together at intervals, and other flanges on said members opposite and spaced apart.

12. A truck frame composed of one metal plate, the two portions of which are opposite and spaced apart, forming side portions thereof, inwardly projecting integral flanges formed on said side portions and adapted to overlap each other, and holes in the outer flanges into which welding material is fused, thereby securing said flanges together.

13. A truck frame composed of a single plate of metal bent on its intermediate line, forming side portions spaced apart and provided with integral inturned flanges, some of which are overlapping and secured together, pedestal tie bars formed integrally with the lower arch bar portion, the outer portion of each of which is composed of a double thickness of plate.

14. A truck frame comprising a pair of side portions, a top portion, a bottom portion and intermediate portions, all pressed and flanged from one plate of metal, some

of the members of which are provided with overlapping flanges welded together through openings in the flanges.

15. A truck frame composed of a single plate of metal bent on its intermediate portion to form two side portions spaced apart, a central bolster opening therein, the upper portion of which is bounded by inwardly projecting overlapping flanges secured together, while the lower portion of the same is bounded by two oppositely disposed flanges, the edges of which are spaced slightly apart.

16. In a truck frame composed of a single plate of metal, the combination with other members, of an inclined tension member extending from the bottom arch bar to near the end portion of the upper arch bar, the bottom portion of said tension member being provided with inwardly turned overlapping flanges terminating near the bend between the same and the integral pedestal tie bar.

17. A car truck side frame including a metal sheet shaped to form inner and outer side walls, each of said side walls being provided with corresponding side frame portions, flanges provided on said side frame portions adapted to extend inwardly of the side walls, portions of said flanges being overlapped and means uniting said overlapped portions.

18. A pressed metal car truck side frame including a plurality of pedestal tie bar portions having inwardly extending continuous marginal flanges, portions of said flanges being overlapped and united on the longitudinal center of the side frame.

19. A car truck side frame involving a wrought metal sheet arranged to form spaced outer and inner walls, each of said walls having a plurality of top arch bar portions, a plurality of bottom arch bar portions, and a plurality of pedestal tie bar portions, said pedestal tie bar portions being provided with inwardly extending portions adapted to be overlapped and connected.

20. The method of manufacturing a car truck side frame which consists in forming from a sheet of metal a blank in duplicate half portions from the same die, bending corresponding portions of the blank to form flanges, folding the blank with portions of said flanges abutted and overlapped, and uniting said abutted and overlapped portions.

In witness whereof I hereunto affix my signature.

LINDSAY C. PRITNER.
